DESIGN FOR A PANCAKE TURNER OR SIMILAR ARTICLE

Robert H. Wendt, Evanston, Ill.

Application September 20, 1946, Serial No. 133,452

Term of patent 14 years

(Cl. D44—29)

To all whom it may concern:

Be it known that I, Robert H. Wendt, a citizen of the United States, residing at Evanston, in the county of Cook and State of Illinois, have invented a new, original, and ornamental Design for Pancake Turners or Similar Article, of which the following is a specification, reference being had to the accompanying drawing, forming part thereof.

Fig. 1 is a top plan view of a pancake turner or similar article, showing my new design; and

Fig. 2 is a side elevational view of a pancake turner or similar article, showing my new design.

I claim:

The ornamental design for a pancake turner or similar article, as shown.

ROBERT H. WENDT.
